CLAIM

The ornamental design for a drawer insert for furniture as shown and described.

DESCRIPTION

1. Drawer insert for furniture
2. Drawer insert for furniture
3. Drawer insert for furniture
4. Drawer insert for furniture
5. Drawer insert for furniture
6. Drawer insert for furniture
7. Drawer insert for furniture
8. Drawer insert for furniture
9. Drawer insert for furniture
10. Drawer insert for furniture
- 1.1 is a top perspective view of a drawer insert for furniture;
- 1.2 is a bottom perspective view of a drawer insert for furniture;
- 1.3 is a front view of a drawer insert for furniture;
- 1.4 is a back view of a drawer insert for furniture;
- 1.5 is a top view of a drawer insert for furniture;
- 1.6 is a bottom view of a drawer insert for furniture;
- 1.7 is a right-side view of a drawer insert for furniture;
- 2.1 is a top perspective view of a drawer insert for furniture;
- 2.2 is a bottom perspective view of a drawer insert for furniture;
- 2.3 is a front view of a drawer insert for furniture;
- 2.4 is a back view of a drawer insert for furniture;
- 2.5 is a top view of a drawer insert for furniture;
- 2.6 is a bottom view of a drawer insert for furniture;
- 2.7 is a right-side view of a drawer insert for furniture;
- 3.1 is a top perspective view of a drawer insert for furniture;
- 3.2 is a bottom perspective view of a drawer insert for furniture;
- 3.3 is a front view of a drawer insert for furniture;
- 3.4 is a back view of a drawer insert for furniture;
- 3.5 is a top view of a drawer insert for furniture;
- 3.6 is a bottom view of a drawer insert for furniture;
- 3.7 is a right-side view of a drawer insert for furniture;
- 4.1 is a top perspective view of a drawer insert for furniture;
- 4.2 is a bottom perspective view of a drawer insert for furniture;

(Continued)

4.3 is a front view of a drawer insert for furniture;
4.4 is a back view of a drawer insert for furniture;
4.5 is a top view of a drawer insert for furniture;
4.6 is a bottom view of a drawer insert for furniture;
4.7 is a right-side view of a drawer insert for furniture;
5.1 is a top perspective view of a drawer insert for furniture;
5.2 is a bottom perspective view of a drawer insert for furniture;
5.3 is a front view of a drawer insert for furniture;
5.4 is a back view of a drawer insert for furniture;
5.5 is a top view of a drawer insert for furniture;
5.6 is a bottom view of a drawer insert for furniture;
5.7 is a right-side view of a drawer insert for furniture;
6.1 is a top perspective view of a drawer insert for furniture;
6.2 is a bottom perspective view of a drawer insert for furniture;
6.3 is a front view of a drawer insert for furniture;
6.4 is a back view of a drawer insert for furniture;
6.5 is a top view of a drawer insert for furniture;
6.6 is a bottom view of a drawer insert for furniture;
6.7 is a right-side view of a drawer insert for furniture;
7.1 is a top perspective view of a drawer insert for furniture;
7.2 is a bottom perspective view of a drawer insert for furniture;
7.3 is a front view of a drawer insert for furniture;
7.4 is a back view of a drawer insert for furniture;
7.5 is a top view of a drawer insert for furniture;
7.6 is a bottom view of a drawer insert for furniture;
7.7 is a right-side view of a drawer insert for furniture;
8.1 is a top perspective view of a drawer insert for furniture;
8.2 is a bottom perspective view of a drawer insert for furniture;
8.3 is a front view of a drawer insert for furniture;
8.4 is a back view of a drawer insert for furniture;
8.5 is a top view of a drawer insert for furniture;
8.6 is a bottom view of a drawer insert for furniture;
8.7 is a right-side view of a drawer insert for furniture;
9.1 is a top perspective view of a drawer insert for furniture;
9.2 is a bottom perspective view of a drawer insert for furniture;
9.3 is a front view of a drawer insert for furniture;
9.4 is a back view of a drawer insert for furniture;
9.5 is a top view of a drawer insert for furniture;
9.6 is a bottom view of a drawer insert for furniture;
9.7 is a right-side view of a drawer insert for furniture;

10.1 is a top perspective view of a drawer insert for furniture;
10.2 is a bottom perspective view of a drawer insert for furniture;
10.3 is a front view of a drawer insert for furniture;
10.4 is a back view of a drawer insert for furniture;
10.5 is a top view of a drawer insert for furniture;
10.6 is a bottom view of a drawer insert for furniture;
10.7 is a right-side view of a drawer insert for furniture.
